(57) **CLAIM**

The ornamental design for a wiring clamp, as shown and described.

DESCRIPTION

FIG. 1 is a perspective view of a wiring clamp showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is an exploded view as shown in FIG. 1 thereof;

FIG. 9 is another perspective view illustrating use of the wiring clamp thereof; and,

FIG. 10 is another perspective view as in FIG. 9 in a final use configuration.
